UNITED STATES PATENT OFFICE.

WILLIAM P. TARRANT, OF SARATOGA SPRINGS, NEW YORK, ASSIGNOR TO TARRANT
MANUFACTURING CO., OF SARATOGA SPRINGS, NEW YORK, A CORPORATION OF
NEW YORK.

STREET-CLEANING APPARATUS.

1,219,505.

Specification of Letters Patent. Patented Mar. 20, 1917.

Application filed April 27, 1914. Serial No. 834,610.

To all whom it may concern:

Be it known that I, WILLIAM P. TARRANT, a citizen of the United States of America, and a resident of Saratoga Springs, Saratoga county, and State of New York, United States of America, have invented certain new and useful Improvements in Street-Cleaning Apparatus, of which the following is a specification, reference being had to the accompanying drawings, forming a part thereof.

My invention relates to street cleaning apparatus and has special reference to hand carts which are adapted to carry a bag or other refuse receptacle and are provided with a dust pan attachment.

One object of my invention is to provide a light and durable device of the aforesaid character that shall embody simple and effective means for guiding and operating the dust pan to either a position to receive refuse from the street or to discharge into the bag or receptacle carried by the cart.

Other objects and advantages of my invention will be set forth hereinafter, and in order that my invention may be thoroughly understood, I will now proceed to describe the same in the following specification and then point out the novel features thereof in appended claims.

Referring to the drawings:

Figure 1 is a side elevation of a street cleaning apparatus arranged and constructed in accordance with my invention.

A front elevation of the same apparatus is shown in Fig. 2.

Fig. 3 is a sectional plan view showing the dust pan attachment and taken on the line 3—3 of Fig. 1.

Fig. 4 is a sectional detail of one of the supports for the actuating frame, taken on the line 4—4 of Fig. 1 and drawn to a larger scale.

Fig. 5 is a sectional detail of the supporting ring which is adapted to support a bag or similar receptacle. This figure is also drawn to a larger scale.

Like characters of reference designate corresponding parts in all the figures.

The cart here shown comprises a frame 10, a pair of relatively large wheels 25, a relatively small guide wheel 26, a dust pan or receiver 30, and an actuating frame 40 therefor.

The frame 10 comprises a pair of spaced

angle bars 11, transverse bars 18 secured thereto, a pair of central uprights 12 having extensions 13 extending at an angle and supporting at their outer ends a transverse handle bar 14; a strap 15 connecting the handle bar 14 with one of the bars 18, and a pair of guide bars 16, constituting a guide frame and attached at the bottom to the forward ends of the angle bars 11, and curved at their upper ends and attached to intermediate points in the extensions 13.

Secured to the uprights 12 are a pair of stub axles 17 on which the wheels 25 are rotatively mounted, the arrangement of parts being such that the frame is supported at a short distance above the ground when the wheels are mounted on the stub axles.

The dust pan 30 has a reinforced edge 31 which is adapted to make contact with the street or ground, and a funnel-shaped body 75 having a rectangular discharge opening 32. The opening 32 is at the upper end of the dust pan when it is in position to receive refuse from the street as shown in Figs. 1 and 2; and near its upper end is secured a transverse reinforcing bar 33, the ends of which extend beyond the sides of the pan and are bent into transverse loops 34 surrounding the guide bars 16 between which the pan is mounted as clearly shown in Fig. 3, to form a lost motion connection therewith.

A second reinforcing rod 19 is secured to the dust pan 30 near its lower edge and terminates in pivoted loops or sleeves 21 which are arranged to slide on the guide bars 16, and co-operate with the loops 34 of the bar 33 in guiding the movement of the pan.

Pivotedly mounted on the stub axles 17 within the wheels are a pair of blocks 41 95 each having a curved edge surface 42 provided with a groove 43.

The actuating frame 40 comprises a pair of curved bars 44 which are respectively seated in the grooves 43 of the blocks 41 100 and are held in position by straps 45. They are tied together at their outer end by a handle bar 46 and at their inner ends they are pivotally connected to pin projections 47 of the dust pan 30. The arrangement is 105 such that the bars 44 slide through the loops 45 of the blocks 41, the grooves 43 constituting guides for maintaining the parts in suitable relations.

Secured to one of the strips 18 is a forked 110

frame 27 on which the wheel 26 is pivotally supported near the central plane of the cart, and above this is a pedal projection 28.

Between the extensions 13 of the uprights 5 12 is removably supported a ring-shaped carrier 48, socket projections 49 which extend from opposite points of the ring, being mounted on studs 49^a on the extensions 13. As clearly shown in Figs. 1 and 5 the ring 10 45 is preferably provided with a plurality of pins 50 which are adapted to hold the cloth bag or similar receptacle after it has been stretched on the ring 48. The ring is 15 reversible so that the spikes may extend either upwardly or downwardly.

The operation of the device is as follows: The hand cart is moved from place to place by the operator who grasps the handle bar 14 and holds the dust pan in an elevated 20 position, by means of the handle bar 46. When he desires to utilize the dust pan attachment he lowers the pan into the position shown in Figs. 1 and 2, by permitting the handle bar 46 and the guide frame to swing 25 about the stub axles 17 as pivots. The refuse is then scraped or swept onto the dust pan and the operator then pulls backwardly on the handle bar 46. This action causes the bars 44 of the actuating frame to slide 30 in the grooves 43 at the same time that the blocks 41 swing on the axles 17 on which they are mounted. The pan itself is first tilted upwardly at its outer edge about the center of the rod 19 as an axis, until the lost 35 motion provided by the loops 34 is taken up. It is then elevated to the position shown in broken lines in Fig. 1, being guided in its entire movement by the guide bars 16. In this position the opening 32 of the funnel-shaped portion of the pan is in position to 40 discharge directly into the bag or receptacle which is supported on the ring 48. This arrangement has the advantage of working very readily and of tilting the pan so as to prevent dropping any of the refuse while 45 the pan is being elevated.

As soon as a bag is filled it is removed and replaced by another, the stretching and supporting ring 48 being removed with the full 50 bag and an empty bag stretched onto it before it is replaced, thereby facilitating the change.

Instead of using a bag, a barrel or can may be set on the frame between the wheels, 55 in position to receive refuse discharged from the dust pan.

The guides 16 are removable, and so is the dust pan and its frame, so that the cart may be used for general purposes without these 60 attachments.

What I claim is:

1. A hand cart comprising a frame constituting a receptacle support and having a guide frame and axle projections, wheels 65 mounted thereon, a dust pan slidably sup-

ported on the guide frame, and a pair of curved arms pivotally and slidably supported on the wheel axles for raising the pan on the guide frame into position to discharge into the receptacle.

2. A hand cart comprising a frame having a handle bar, a pair of substantially parallel guide bars secured to the frame, a dust pan having pivots slidably supported on said guide bars, means for limiting the 75 rotative movement of the pan about its pivot and manual means for tilting the pan about said pivot through said rotative movement before the pivots are slid on the guide bars.

3. A hand cart comprising a frame constituting a receptacle support having a handle bar, a pair of substantially parallel guide bars secured to the frame, a dust pan having pivots slidably supported on said 85 guide bars, means for limiting the rotative movement of the pan about its pivots, and means for tilting the pan through said rotative movements before the pivots are slid on the guide bars, and then sliding the 90 pivots and rotative limiting means on the guide bars to raise and guide the dust pan into position to discharge into the receptacle.

4. A hand cart comprising a frame having a handle bar, a pair of substantially parallel guide bars secured to the frame extending vertically in front of the cart and bent at their upper ends backwardly and downwardly, a dust pan having pivots slidably supported on said guide bars, means for limiting the rotative movement of the pan about its pivots and manual means for tilting the pan about its pivots and for sliding said pivots and the rotative limiting 105 means on the guide bars.

5. A hand cart comprising a frame constituting a receptacle support having a handle bar, a pair of substantially parallel guide bars secured to the frame extending 110 vertically in front of the cart and bent at their upper ends backwardly and downwardly, a dust pan having pivots near the lower back portion thereof slidably supported on said guide bars, loops near the 115 top of the dust pan encircling the guide bars for limiting the rotative movement of the pan about its pivots, and means for first tilting the pan through said limited rotative movement and then sliding said pivots 120 and loops on the guide bars to raise and guide the dust pan into position to discharge into the receptacle.

6. A hand cart comprising a frame having laterally extending axle projections, a 125 handle bar, a pair of substantially parallel guide bars secured to the frame, a dust pan having pivots slidably supported on said guide bars, means for limiting the rotative movement of the pan about its pivots, and 130

levers pivotally and slidably supported on the wheel axles and pivoted at one end to the dust pan.

7. A hand cart comprising a frame, having laterally extending axle projections, a handle bar, a pair of substantially parallel guide bars secured to the frame, a dust pan having pivots slidably supported on said guide bars, means for limiting the rotative movement of the pan about its pivots, guide blocks pivotally mounted on the wheel axles and having edge grooves, a pair of actuators

ing levers slidably supported in the grooves of said blocks and pivotally connected to the pan at points in advance of the axis of 15 the pan.

In witness whereof, I have hereunto set my hand, in the presence of two subscribing witnesses, this 22d day of April, 1914.

WILLIAM P. TARRANT.
